BY

ATTORNEY.

UNITED STATES PATENT OFFICE.

DENTON E. PLUMLEE, OF SEGO, UTAH.

DESIGN FOR A GAME APPARATUS.

56,833.

Specification for Design.

Patented Dec. 28, 1920.

Application filed July 13, 1920. Serial No. 396,023. Term of patent 7 years.

To all whom it may concern:

Be it known that I, DENTON E. PLUMLEE, a citizen of the United States, residing at Sego, in the county of Grand and State of Utah, have invented a new, original, and ornamental Design for a Game Apparatus, of which the following is a specification and illustrated in the accompanying drawing, forming a part hereof, wherein:

Fig. 2 is a longitudinal sectional view of the same.

I claim:

The ornamental design for a game apparatus as shown.

DENTON E. PLUMLEE.
